UNITED STATES PATENT OFFICE.

HERBERT E. GETCHELL, OF WOONSOCKET, RHODE ISLAND.

GOLF TEE.

Application filed May 1, 1925. Serial No. 27,288.

To all whom it may concern:

Be it known that I, HERBERT E. GETCHELL, a citizen of the United States, residing at Woonsocket, in the county of Providence and State of Rhode Island, have invented a new and useful Golf Tee, of which the following is a specification.

This invention relates to a golf tee for practice and playing. The principal object of the invention is to provide a simple, durable, and inexpensive tee that is not likely to get lost in practice and that will not be almost necessarily thrown a long distance every time the ball is hit.

Reference is to be had to the accompanying drawings in which

Fig. 1 is a side view showing the tee in position in the ground and the ball, teer, and also the driver in position for driving;

Fig. 2 is a sectional view through the center of the tee in position;

Fig. 3 is a side view of the tee, and

Fig. 4 is a plan.

I am aware of the fact that wooden tees have been made with a concave top to receive the ball and set down into the ground for use in playing. These are open to the objections that every time the ball is driven the tee is apt to be pulled up and cast a long distance or else entirely destroyed. This invention is designed to secure the advantage of such a tee without these difficulties. For this purpose the tee is formed of a piece of wood turned to a conical form to provide a spur 10 to be pressed into the ground and it is cut off at the top on a line 11 to form an angle with the axis of this conical spur. This top is hollowed out to form a cup 12.

In placing this in the ground it is forced in at such an angle as to leave the surface 11 horizontal as indicated in Figs. 1 and 2 with the spur projecting backward in the direction from which the ball is to be driven. Now the ball 13 is placed in the cup, which is small but large enough to retain the ball in position, and it is driven by the driver 14 from the side indicated in Fig. 1.

It will be observed that in case the stroke is made too low it will not be apt to tear up the tee from the ground but will press it forward and ordinarily cannot drive it far out of its hole in the ground. In ordinary practice the tee will not be disturbed in any

way and will remain in position for a number of practice strokes but the main advantage is that even if it is hit by the club it will not tear up the ground and the tee will not be driven far enough away to be lost or necessitate any search for it. The spur is made of conical form so as to be pressed in easily and so as not to present any weak point at which it is likely to break in two.

I have spoken of this tee as formed of wood which would be the natural material for it, but if desired it may be molded of hard rubber, paper, or any other desired material which might be advantageous when made in very large quantities and I do not wish to be limited to the material.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:

1. As an article of manufacture, a golf tee having a horizontal concave flat surface at the top to provide a support for the ball and having a spur projecting downwardly therefrom in a backward direction.

2. As an article of manufacture, a golf tee having a flat surface at the top cupped out to provide a support for the ball and having a spur projecting downwardly therefrom with its axis at an angle to the plane of the top surface.

3. As an article of manufacture, a golf tee having a surface at the top cupped out to provide a support for the ball and having a spur of conical form projecting downwardly therefrom in a backward direction to hold it in the ground if it is hit.

4. As an article of manufacture, a golf tee having a horizontal surface at the top to provide a support for the ball and having a spur projecting downwardly therefrom with its axis at an angle to the plane of the top surface, said spur tapering all the way from said horizontal surface to provide strength.

In testimony whereof I have hereunto affixed my signature.

HERBERT E. GETCHELL.
